UNITED STATES PATENT OFFICE.

ORRIL R. CHAPLIN, OF BOSTON, MASSACHUSETTS.

SASH-FASTENER.

SPECIFICATION forming part of Letters Patent No. 453,177, dated June 2, 1891.

Application filed February 6, 1891. Serial No. 380,467. (No model.)

To all whom it may concern:

Be it known that I, ORRIL R. CHAPLIN, of Boston, in the county of Suffolk and State of Massachusetts, have invented certain new and 5 useful Improvements in Window-Fasteners, of which the following, taken in connection with the accompanying drawings, is a specification.

My invention relates to window-fasteners 10 for securing together the upper and lower sashes of windows having vertically-movable sashes; and it consists in certain novel features of construction, arrangement, and combination of parts, which will be readily understood by reference to the description of the drawings and to the claims hereinafter given, and in which my invention is clearly pointed out.

Figure 1 of the drawings is an elevation of 20 a window with my improved fastener applied thereto, the same being shown with the sashes closed and locked and viewed from the interior of the room. Fig. 2 is a vertical section on line x on Fig. 1, looking toward the right 25 of said figure, and showing both sashes moved from their normal or closed positions and locked together. Fig. 3 is a plan of that portion of the fastening which is secured to and moves with the lower or inner sash. Fig. 4 is an inverted plan of the same, partly in section. Fig. 5 is a central vertical section of 30 the base of the same, and showing the fastening-lever and the spring in elevation; and Fig. 6 is a plan of the locking-latch detached.

35 In the drawings, A is the lower sash, B the upper sash, C C portions of the window-frame, D the window-sill, a a a the stop-beads, and b the parting-bead, all of which are of ordinary construction.

40 To the upper or meeting rail c of the lower sash is secured the base-plate d of the fastener, made in the form of a shallow inverted cup and having pivoted to its center the fastening-lever E, provided at its front end with 45 the finger-pad e and the downwardly-projecting lug e', and having formed in the side of its rearwardly-projecting arm the open slot e², which engages the post F between two of the collars f, formed thereon, to fasten the two 50 sashes together, either in a closed position or in a partially-opened position, as shown in Fig. 2.

The post or column F has formed thereon the base-flange f', by which and the screws f² it is firmly secured to the lower or meeting 55 rail of the upper sash B in an upright position, and has formed thereon a series of circumferential grooves g, each of a vertical width equal to or slightly greater than the vertical depth of rear or hook end of the lever 60 E, said grooves g and the collars f being so arranged on said post or column that the lower groove shall be in position to receive the slotted end of the lever E when the two 65 sashes are tightly closed, as shown in Fig. 1.

The base-plate d has formed in its cylindrical wall two rectangular slots d' and d² and in its upper surface the slot d³, curved concentric to the axis of the pivot about which the lever E moves in fastening and unfastening 70 the window.

The lever E has set in its under side the pin h, which projects through the slot d³ into the chamber of the base-plate d, as shown in 75 Figs. 4 and 5.

H is the locking-latch-lever provided with the operating-arm h' and with the shoulders i and i', one at each end of the curved wedge-like expansion h², which projects through the slot d', while the arm h' projects through the 80 slot d³, as shown in Figs. 1, 2, 3, and 4. The shoulder i of the latch-lever H rests against the right-hand end of the slot d', with the toe i' bearing against the inner surface of the 85 wall of the chamber, against which it is pressed by the tension of the scroll-spring j, the outer end of which is connected to the locking-lever H by having a portion thereof bent at right angles to its main body and inserted in the hole i², formed in said lever near the shoulder 90 i, while the inner end of said spring is attached to the end of the pin h, as shown in Fig. 4. By this construction and arrangement of the fastening-lever E, the locking-latch H, and the spring j a single spring is made to serve the 95 purpose of holding the fastening-lever E in either its engaged or disengaged position, and also to press the locking-latch H outward, as shown. This is accomplished by virtue of the fact that the inner end of the scroll-spring 100 is attached to the pin h, which, when the lever E is moved from one extreme of its movement to the other, travels in a curved path concentric to the axis of motion of said lever and

from a point on one side of a radial line $l\ l$ drawn through said axis and point of attachment of the outer end of said spring to the latch-lever H to a point upon the opposite side of and about the same distance from said line. When the lever E is moved in either direction, the spring j tends to resist such movement until the pin h reaches a point on the line $l\ l$; but when said pin has passed said line the tension of the spring tends to move said pin toward the end of the slot d^3 , the ends of which serve as stops to limit the movement of the lever E in either direction.

By the use of my improved fastening the window-sash may be securely locked together either in a closed position or when partially opened for the purpose of ventilation, and may be so adjusted as to be open at the bottom or top, or both top and bottom, and still be secure against attacks of outsiders, except by breaking the glass.

In some cases, where it is only desired to fasten the window in a closed position, the post F would be made only of sufficient height to have formed thereon the lower groove g , all of said post above the lower collar f being omitted.

I claim—

1. The combination, in a window-fastener, of a post or column to be secured to the meeting-rail of the upper sash and provided with a circumferential groove, a base-plate to be secured to the meeting-rail of the lower sash, a two-armed lever pivoted to said base-plate so as to be movable about said pivot in a horizontal plane, and provided on its front arm with a pendent lug and having its rear arm constructed and arranged to engage the groove in said post, stops to limit the movement of said lever in both directions, a latch-lever for locking said two-armed lever in engaged position, and a spring for controlling the action of said latch-lever.

2. The combination, in a window-fastener, of a post or column to be secured to the meet-

ing-rail of the upper sash and provided with a series of circumferential grooves formed thereon one above the other, a base-plate to be secured to the meeting-rail of the lower sash, a two-armed lever mounted upon said base by a vertical pivot and provided on its front arm with a pendent lug and having its rear arm constructed and arranged to engage either of the grooves on said post or column, and a spring-pressed latch for locking said lever when in engaged position.

3. The combination of a pivoted lever constructed and arranged to be vibrated about its pivotal connection, stops to limit the movement of said lever in both directions, and a scroll-spring having its outer end pivoted in a bearing intermediate between the two extremes of the angular movement of said lever and its inner end connected to said lever, so that said spring shall tend to press said lever against its stop at either extreme of its movement.

4. The combination of the inverted-cup-like base-plate d , provided with the slots d' , d^2 , and d^3 , the lever E , pivoted to said base-plate and provided at one end with the slot e^2 and at its other end with the lug e' , the locking latch-lever H , the pin h , set in the lever E and projecting through the slot d^3 , the scroll-spring j , connected at one end to the latch-lever H and at its other end to the pin h , and the post or column F , constructed and adapted to be secured to the meeting-rail of the upper sash and provided with a series of grooves or notches to receive the inner end of the lever E , substantially as described.

In testimony whereof I have signed my name to this specification, in the presence of two subscribing witnesses, on this 5th day of February, A. D. 1891.

ORRIL R. CHAPLIN.
